UNITED STATES PATENT OFFICE.

THOMAS G. SPENCER, OF ROCHESTER, NEW YORK, ASSIGNOR TO THE HOLLISTER LUMBER COMPANY, OF ROCHESTER, NEW YORK, A CORPORATION OF NEW YORK.

FOLDING TABLE.

1,331,538.

Specification of Letters Patent. Patented Feb. 24, 1920.

Application filed October 6, 1919. Serial No. 328,755.

To all whom it may concern:

Be it known that I, THOMAS G. SPENCER, of Rochester, in the county of Monroe and State of New York, have invented certain new and useful Improvements in Folding Tables; and I do hereby declare the following to be a full, clear, and exact description of the same, reference being had to the accompanying drawings, forming a part of this specification, and to the reference-numerals marked thereon.

My present invention relates to furniture, and more particularly, to such articles as folding tables, though it is applicable to any element, such as a table top that is foldable and is held in a given position by a folding brace and the invention has for its object to provide a simple, inexpensive and convenient construction of the bracing mechanism whereby the table top, or other element, may be securely held in its operative position but readily folded into a compact and secure inoperative position. To these and other ends the invention resides in certain improvements and combinations of parts, all as will be hereinafter more fully described, the novel features being pointed out in the claims at the end of the specification.

In the drawings:

Fig. 1 is a side view of a folding table in operative position and constructed in accordance with, and illustrating one embodiment of my invention.

Fig. 2 is a longitudinal sectional view of the table in folded position.

Fig. 3 is a bottom view of the table extended for use.

Fig. 4 is an enlarged detail section of a fragment of the brace, and adjacent portions of the table top showing a means for holding it in folded position;

Fig. 5 is a bottom view of the table folded;

Fig. 6 is an enlarged fragmentary view in section through the brace and its connections, showing it in operative position;

Fig. 7 is a similar view illustrative of the manner of releasing the brace from its locking abutments and

Fig. 8 is an enlarged fragmentary section showing the manner in which the brace cooperates with its locking abutments.

Similar reference characters in the several figures indicate the same parts.

In the present instance I have illustrated

my invention as applied to a table of a familiar type embodying a top 1 and two pairs of legs 2 and 3, the legs of each pair being connected together by a rail 4 and hinged to the table top at 5 so that the pairs 60 of legs fold toward each other flat against the under side of the table top from the position of Figs. 1 and 3 to that of Figs. 2 and 5. This invention has reference to the mode of bracing these legs in their operative position and as the structure is the same with respect to both pairs of legs a description of one will suffice for both.

The brace that I prefer to employ is indicated at 6 and may consist of a metal rod 70 bent into a yoke shape with one of its connecting portions hinged to the rail 4 at 7, so that as the table legs are folded or extended with reference to the top 1 the other connecting portion 8 will traverse the under side of 75 the top with a substantially longitudinal movement. Secured to the under side of the top 1 is a fixed abutment 9 and a movable abutment 10. The former is of a cam shaped contour on its outer side, as indicated at 11, 80 the cam leading to a concave engaging shoulder 12.

The other and movable abutment comprises a spring finger 13 having a thin portion 14 secured beneath a strap 15 on the 85 under side of the top 1 and its enlarged portion provided with a finger piece 16, so that it may be manually flexed outwardly and drawn away from its normal position against the face of the top. Both abutments 90 are preferably made of wood and added resiliency is given to the spring finger 13 of the movable abutment by a metal leaf spring 17 having a closely superposed relationship and also secured beneath the strap 95 15. The engaging shoulder 18 on the movable abutment is also concaved and is spaced from its companion abutting shoulder 12 just sufficiently to admit of the engagement of the connecting portion 8 of the brace 6 100 with both at the same time, so that said connecting portion may be held closely between the two.

In operation, the legs being in the folded position Figs. 2 and 5, when they are swung to extended position the brace 6 that has been lying substantially flat against the under side of the top with its connecting portion 8 in the recess formed by the finger portion 16 of the spring finger 13, is drawn 110

along toward the fixed abutment 9 displacing the spring finger 13, as shown in Fig. 7. It rides over the cam surface 11 against which it is held by the resiliency of the finger until halted by engagement with the shoulder 18 of the movable abutment which thus defines the limit of extension of the legs. The movable abutment and its spring finger then snap back into normal position 10 against the top 1, as shown in Fig. 6, which brings the connecting portion 8 of the brace also into engagement with the shoulder 12 of the fixed abutment. The brace is then held against endwise movement in both directions and the legs are securely held in place.

When it is desired to fold the legs the spring finger 13 is flexed outwardly by means of the finger portion 16. There is a 20 projecting portion 19 thereon adjacent to and forming part of the abutment shoulder 18 that carries the portion 8 of the brace out of the engaging shoulder 12 of the fixed abutment and on to the cam surface 11 of the latter, as shown in Fig. 7. The legs may then be folded down against the under side of the top without further opposition, the brace retraversing the cam surface and sliding beneath the spring finger 13 back to its 30 original position.

To assist in maintaining the legs in folded position I provide a spring catch 20 on the under side of the top that has a concavity 21 adapted to automatically engage with and 35 grip the knuckle 22 of the hinge 7 by means of which the brace is secured to the rail 4 of the legs, all as shown in detail in Fig. 4.

I claim as my invention:

1. The combination with a support and a 40 folding brace connected thereto of an element to be supported having a swinging relationship with the support and provided with two locking abutments, for the brace, one of which is movable relatively to the 45 other and is adapted to dislodge the brace from the latter.

2. The combination with a support and a 50 folding brace connected thereto, of an element to be supported having a swinging relationship with the support, and provided with two abutments for preventing longitu-

dinal movement of the brace, one of said abutments comprising a spring finger movable relatively to and operating to maintain the brace in engagement with the other. 55

3. The combination with a support and a folding brace connected thereto, of an element to be supported having a swinging relationship with the support, and provided with two abutments for preventing longitudinal movement of the brace, one of said abutments comprising a spring finger movable relatively to and operating to maintain the brace in engagement with the other, and adapted, when actuated against its tension 60 to dislodge the brace from the other abutment. 65

4. The combination with a support and a folding brace connected thereto, of an element to be supported having a swinging relationship with the support, and provided with two abutments for preventing longitudinal movement of the brace, one of said abutments being fixed and cam shaped to permit the brace to ride into locking engagement therewith and the other comprising a spring finger operating to maintain the brace in engagement with the first and also in engagement with the cam surface thereof. 70 75

5. The combination with a support and a folding brace connected thereto, of an element to be supported having a swinging relationship with the support, a fixed abutment on said element for preventing longitudinal movement of the brace in one direction, a strap thereon, a movable abutment secured beneath the strap to prevent longitudinal movement of the brace in the other direction and comprising a spring finger 80 adapted to hold the brace in engagement with the first abutment and a spring also secured beneath the strap to reinforce the resiliency of the spring finger. 85

6. The combination with an element to be supported and a support hinged thereto to 90 fold against the same, of a brace coöperating with the said element and hinged to the support and a spring clip on said element adapted to engage the knuckle of the brace hinge when the brace is folded and maintain the 100 latter in such folded position.

THOMAS G. SPENCER.
